Geo. P. Kimmel. ATTORNEY.

UNITED STATES PATENT OFFICE.

ALOIS MERKE, OF CHICAGO, ILLINOIS.

MASSAGE APPLIANCE.

Application filed November 4, 1927. Serial No. 231,082.

This invention relates to a massaging device, designed primarily for use for the treatment of the scalp, but it is to be understood that a device in accordance with this invention, 5 may be employed for any purpose for which it is found applicable, and the invention has for its object to provide, in a manner as hereinafter set forth, a device of the class referred to and of the suction type 10 with means whereby that portion of the scalp or skin to be treated may be placed under tension and massaged without direct contact therewith of the fingers of the masseur.

A further object of the invention is to provide, 15 in a manner as hereinafter set forth, a device of the class referred to including a flexible cup for surrounding a part of the scalp or skin to be massaged and further with the device including spring controlled 20 means communicating with the cup for expeditiously creating a suction action on such part to tension the same whereby the beneficial effect obtained from the massaging of such part will be enhanced.

25 A further object of the invention is to provide, in a manner as hereinafter set forth, a device of the class referred to for expeditiously blowing off dandruff from the scalp when the latter is being massaged by the 30 device.

Further objects of the invention are to provide, 35 in a manner as hereinafter set forth, a massage device which is simple in its construction and arrangement, strong, durable, compact, thoroughly efficient in its use, conveniently operated, capable of being used with or without a suction action upon the scalp or skin, readily assembled, and comparatively inexpensive to manufacture.

40 With the foregoing and other objects in view the invention consists of the novel construction, combination and arrangement of parts as hereinafter more specifically described, and illustrated in the accompanying 45 drawings, wherein is shown an embodiment of the invention, but it is to be understood that changes, variations and modifications can be resorted to which fall within the scope of the claim hereunto appended.

50 In the drawings wherein like reference characters denote corresponding parts throughout the several views:

Figure 1 is a side elevation of a massaging device in accordance with this invention.

Figure 2 is a longitudinal sectional view 55 thereof.

Figure 3 is a section on line 3—3 Figure 2.

Figure 4 is a section on line 4—4 Figure 2.

A massaging device, in accordance with this invention, includes a spring controlled 60 handle element and a cup element communicating with the former. The handle element functions to create a suction within the cup element to apply tension to the part of the scalp or skin which is to be massaged, and 65 with the cup element being formed with massaging tips capable of being employed with or without a tensioning action applied to the scalp or skin.

The handle element includes a tubular 70 body portion 1 of uniform diameter throughout formed of resilient material impervious to air, such as rubber of the desired thickness and which has its inner and outer ends open.

Positioned against the outer end of the body 75 portion 1, for the purpose of closing said end is a head piece 2 formed of any suitable material, preferably hard rubber and which is of greater diameter than the body portion 1, as well as being of materially greater 80 thickness than the thickness of the latter.

The head piece 2 is in the form of a disc preferably corresponding in contour to the contour of the body portion 1. The inner

face of the head piece 2 is provided with an 85 annular groove 3 of a diameter greater than the outer diameter of the body portion 1.

The head piece 2 abuts against the outer end edge of the body portion 1 and the latter is surrounded by the groove 3. Anchored in 90

the groove 3 and extending inwardly from the head piece 2 is a resilient, combined coupling and sealing band 4 which surrounds the outer end of the body portion 1 and is secured thereto.

95 The inner end of the body portion 1 abuts against and is closed by the cup element referred to generally at 5. The body portion 1 provides an air receiving chamber 6 and arranged therein is a coiled spring 7, having 100 one end thereof, as at 8 anchored in the head piece 2 and its other end, as at 9 anchored in the cup element 5. The spring 7 normally retains the handle element in an extended position.

The body portion 1 abuts against the cup element 5 and surrounding a part of the latter, as well as being secured thereto is 105 a rearwardly extending, resilient, combined

sealing and coupling band 10 which overlaps the forward end of the body portion and is secured to said forward end.

The cup element 5 comprises circular base 5 11 having integral therewith and extending therefrom a flaring cup shaped body portion 12 formed of resilient material impervious to air. The body portion 12 is of materially less thickness than the thickness 10 of the base 11 and the latter has a peripheral bead or shoulder 13 against which abuts the sealing band 10.

The base 11 is formed with a series of ports or openings 14 for establishing communication between the body portion 12 and the chamber 6. The end of the spring 9 is anchored in the base 11. Formed integral with the base 11 and surrounded by the body portion 12, as well as being spaced 20 therefrom, in a series of resilient tips or fingers 15 of different lengths and of tapered contour. The tips or fingers 15 are provided for massaging and the length thereof is materially less than the depth of the cup 25 shaped body portion 12.

The body portion 12 can be swung towards the head piece 3, in a manner as indicated in dotted lines in Figure 2, to enable the employment of the tips 15 independently 30 of the body portion 12 when desired.

When the device is employed to create tension on a part of the scalp or the skin the cup element 5 is positioned to surround a part of the scalp or skin and with the handle 35 element compressed and on relieving pressure on the handle element it will expand thereby creating suction within the body portion 12 and applying tension to the skin. That part of the scalp or skin which is under tension can then be massaged by the 40 tips 15. If it be desired to use the device without employment of the body portion 12,

the latter is swung to the position shown in dotted lines, and the scalp or skin massaged with the tips 15 and by compressing the 45 handle element 1 the dandruff will be blown off.

It is thought the many advantages of a massaging device, in accordance with this 50 invention and for the purpose set forth, can be readily understood, and although the preferred embodiment of the invention is as illustrated and described, yet it is to be understood that changes in the details of construction can be had which will fall within 55 the scope of the invention as claimed.

What I claim is:

A massage device comprising a resilient cup element provided therein with massaging tips and further provided with ports 60 arranged between the rear ends of and extending rearwardly from the tips, a resilient tubular handle element of uniform diameter having its forward end abutting the rear face of the cup element, an annular member 65 secured to and surrounding said elements for connecting them together and providing an air tight joint, a closure having its inner face abutting the other end of and of greater diameter than the handle element, 70 an annular member surrounding the handle element and extending into said closure, secured to the latter and handle element for connecting them together and providing an air tight joint, and a coiled spring positioned 75 in the handle element and abutting the inner face of the closure and rear face of the cup element, said spring having one end anchored in the rear face of the cup element and its other end in the inner face of said closure.

In testimony whereof, I affix my signature hereto.

ALOIS MERKE.
